MACHINE FOR DRIVING TUBES INTO
HEELS

Frank T. Gentile, Brooklyn, N. Y., assignor to
United Shoe Machinery Corporation, Paterson,
N. J., a corporation of New Jersey

Application October 14, 1932, Serial No. 637,735

23 Claims. (Cl. 12—42)

This invention relates to the driving of tubes into wooden heels, and is illustrated as embodied in a machine for making heels of the type illustrated in United States Letters Patent No. 1,725,810, granted August 27, 1929, on the joint application of Fred Maccarone and myself.

The patent referred to discloses a wood heel having a triangular tube inserted in its top-lift end. This tube receives a closely fitting shank attached to a top-lift, which is designed to be replaceable. The top-lift shank is longitudinally notched from its inside end for a part of its length, and the tube in the heel is correspondingly indented, the indentation spreading the sides of the notch to make the shank engage the interior of the tube firmly.

An important object of the present invention is to provide a machine which will take plain tubes, and drive them into previously drilled heels. To this end I have provided a machine having a heel supporting means, a tube holding means, and a tube driver arranged to insert a tube in a heel supported on the supporting means. In accordance with an important feature of the invention means is provided for indenting the tubes as they are driven. Inasmuch as, while the tubes may vary in length, the top-lift shanks are preferably all alike, means is provided for insuring that the indentation formed will always be at the same distance from the outside end of the tube, irrespective of the length of the tube, to enable it to cooperate properly with the top-lift shank.

Accordingly, in the illustrated machine I have provided a driving tool and an indenting tool, with provision for adjustment between them so that the outside or following end of a tube to be driven may always be presented to the indenting tool in the same relation, irrespective of the length of the tube.

These and other features of the invention comprising certain combinations and arrangements of parts will be apparent from the following description of a preferred embodiment of the invention shown in the drawings, in which

Fig. 1 is a side elevation;

Fig. 2 is a front elevation;

Fig. 3 is a bottom plan of the top-lift end locating device;

Figs. 4 and 5 are rear elevations of the transfer member;

Fig. 6 is a section on the line VI—VI of Fig. 5;

Fig. 7 is a broken away view of the heel, tube and driver; and

Fig. 8 is a section on the line VIII—VIII of Fig. 7.

The frame 10 has mounted on its lower portion a standard 12 bearing a vertical screw 14 which is adjustable by means of a hand nut 16. At the upper end of the screw 14 is a toothed segment 18 which is angularly adjustable about a horizontal axis 20. This segment is adapted to contact with and support the attaching face of a heel 22 having a hole 24 into which it is proposed to drive a tube 26 (see Fig. 7). The upper part of the frame carries a horizontal shaft 28 driven by a pulley 30 through a one revolution clutch 32 operated by a convenient treadle (not shown). The operative end of the shaft 28 carries a disk 34.

On the rear side of the disk is a stud 36 carrying an anti-friction roll upon which rests a bail 38 the ends of which carry two rods 40, 42 sliding in guides 44 on the frame. These rods carry 20 collars 46 which confine springs 48 between them and the guides 44, the springs tending to force the rods 40, 42 downwardly. At the lower end of the rods 40 and 42 is carried a plate 50, which has a hole 51 in it, large enough to permit passage of the driver and tube, as will be described below (see also Fig. 3, which shows a bottom plan view of the mechanism mounted on the plate 50). This plate has a screw 52 threaded into an ear 54 thereon by means of which a plate 56 is slidably adjustable along the plate 50. The plate 56 has a slideway in which a plate 58 is adjustable transversely to the axis of the screw 52 by means of thumb screws 60, 62. The plate 58 is deeply notched at 64. The plate 50 also carries a rib 66 into which a screw 68 is threaded by means of which a slide bar 70 is adjustable parallel to the axis of the screw 52. Two rods 72 are slidably mounted in the bar 70 and carry on their ends a bar 74. The rods 72 are surrounded by springs which tend to separate the bar 70 and the bar 74. The edges of the notch 64 and that edge of the bar 74 which faces the notch 64 are beveled or rounded off at 76 so that when the mechanism shown in Fig. 3 is forced downwardly upon the top-lift end of the heel 22 the bar 74 will be wedged away from the plate 58 and its edge and the edges of the notch 64 will embrace and hold the top-lift end of the heel 22, as shown 50 in Fig. 3. The top-lift end of the heel then abuts upon the plate 50. The heel will thus be firmly supported on the segment 18 against vertical pressures, and gaged relatively to the driving tool.

A driver 78 is removably mounted in a block 55

80 which is arranged to slide vertically in the frame of the machine.

The block 83 is pivotally connected at 82 to a link 84 which is adjustable in length by means 5 of a right and left screw at 86 and has its other end pivoted at 88 to a stud mounted on the front side of the disk 34. The rotation of the disk will therefore move the driver 78 up and down. The driver 78 has a reduced portion 90 at its 10 lower end marked off by a shoulder 92 in the shank of the driver. The portion 90 is shaped in cross-section like the cross-section of the tube 26 which it is proposed to drive into the heel. The illustrated tube is triangular.

15 The reduced portion 90 has a groove 92a along its rear side for a purpose which will be now explained. A chisel 94 is mounted to slide horizontally forward and back in the frame of the machine. It has a beveled rear end 96, its front 20 end 98 bearing the chisel edge. This chisel is forced toward the line of action of the driver by a beveled end 100 on a plunger 102 which is normally forced upwardly by a spring 104 and slides in a slideway 106 in the frame. The plunger 25 102 is driven downwardly by a cam 108 adjustably mounted on the disk 34. The drive is so timed that the chisel 94 is thrust toward the driver 78 as it is moving a sleeve in the presser member to be described past the chisel end 98, 30 thus forming a depression or indentation 110 in the tube 26 as it is carried downward by the driver.

35 It is desirable that the indentation 110 be made in the tube at a definite distance from its outer end (when in the heel) in order that it may cooperate properly with the slot in the top-lift shank. The adjustment at 86 permits the relative timing of the chisel movement and the movement of the driver so that the chisel and the shoulder 92 will be in the desired relation at the 40 instant of indentation. Inasmuch as the shoulder 92 contacts with the end of the tube and supplies the driving pressure, the indentation 110 will be formed at the right distance from the 45 end of the heel.

50 The tubes 26 are fed to the driver through a raceway 112 having a groove in it shaped to fit the outside of the tubes so that they will be delivered to the driver with a flat side to the rear, as seen in Fig. 2. As they run down the raceway 112 they run into a transfer member 114, see more particularly Figs. 4, 5, and 6. This transfer member 114 is a cylinder oscillating around a horizontal axis in a block 116 mounted 55 in the frame. The rear end of the cylinder is recessed, the recess having a Y-like formation. This recess has one straight wall 118 extending clear from one side of the cylinder to the other. This wall contacts with an oblique wall 124 of the tube 26. The adjacent wall 122 in the transfer member contacts with the other oblique wall of the tube but does not extend entirely through the transfer member from one side to the other. It stops short at a point 126 and is then connected to the periphery of the transfer member by a diverging wall 128 having a shoulder 130. This transfer member is rotatable between the 60 positions shown in Figs. 4 and 5 by mechanism which will be later described.

65 70 The recess in the transfer member has its rear side closed by a flat surface 132 on the frame of the machine. This surface 132 and the walls 118 and 122 make an easy working fit with the sleeve 26. When the transfer member is in the position 75 shown in Fig. 4, the line of tubes 134, 136

slides down until the lower tube 134 comes against the surface of the circular bore in the block 116 in which the member 114 is mounted. When the transfer member is rotated counterclockwise, as seen from the front of the machine, to the 5 position shown in Fig. 5, the second tube 136 falls on to the shoulder 130 and is thus kept from interfering with the tube 134 which has been turned into a vertical position for driving. The tube in this position is prevented from falling 10 out of the transfer member by a notched member 138 which slightly overlaps the end of the tube and has the edges of its notch beveled so that downward pressure of the tube will force it to slide backward against a spring 140, thus 15 allowing the tube to pass through. This lug 138 is supported by a plate 142 on the machine frame.

15 It will be readily seen that when the machine is tripped the driver 78 and plate 50 will begin to descend. The plate 50 descends upon the heel 20 22 and firmly clamps and gages its top-lift end in position under the driver. The driver 78 descends through a hole 144 in the block 116 and enters the tube 134 which abuts the shoulder 92 at the end of the reduced portion 90 of the 25 driver. The driver thus lowers and guides or supports the tube 134 and as the cam 108 comes around and presses down on the end of the plunger 102 the chisel edge 98 is actuated to crush the rear side of the tube into the depression 92a 30 in the driver, thus forming the inwardly directed rib 116 in the tube. Further movement of the disk 34 releases the chisel 98 and forces the tube downward into the heel 22. The height of the heel support 18 is adjusted by the screw 14 so 35 that the top-lift end of the heel will just register with the shoulder 92 when the driver is in its lowest position.

40 The transfer member 114 is controlled as follows. The stud mounted in the disk 34 at 88 has pivoted upon its extremity a link 148 having a long slot 150 in it the upper end of which embraces the stud at 88. This link is pivoted at 160 to a lever 162 pivoted at 164 on the machine frame. The other end 166 of the link is pivoted 45 to a link 168, the other end of which link is pivoted to a pin 170 on the transfer member 114. This pin 170 and a similar pin 172 work in arc-shaped slots in the block 116, as shown in Fig. 2. The pin 172 is connected to a pin 174 on the 50 frame by a spring 176. The spring thus tends to move the transfer member into the position shown in Fig. 5, that is, the driving position. When the machine is in stopped position, as shown in Fig. 2, the stud 88 has pulled the link 55 148 to its uppermost position, thus pulling the transfer member clockwise, as seen from the front of the machine, into the position shown in Fig. 4, against the spring pull. As the disk 34 starts to revolve the stud 88 releases the link 148 and the 60 spring 176 begins to pull the transfer member into the position shown in Fig. 5, which it reaches before the reduced portion 90 of the driver or the chisel 98 have engaged the sleeve 134 then in the transfer member. The transfer member 65 remains in the position shown in Fig. 5 until the driver has descended, inserted the tube in the heel, and rises again out of the transfer member, that is, until the stud 88 has nearly reached its uppermost position. The stud 88 then turns 70 the transfer member into the Fig. 4 position, permitting the next tube 136 to slide over the corner 126 and to fall into the position occupied by the tube 134 shown in Fig. 4. The plate 50 is also raised in a similar way. The stud 36 lifts the 75

bail 38 and the plate 50 is raised as the stud 36 approaches its uppermost position, as shown in Fig. 2. The operator can then remove the heel 22 and substitute a new one.

5 Having described my invention, what I claim as new and desire to secure by Letters Patent of the United States is:

1. In a machine for driving tubes into heels, a heel support, a tube holder, a member arranged 10 to enter the interior of a tube and to support an inside wall thereof, a tube driving tool, and a tube indenting tool.

2. In a machine for driving tubes into heels, a heel holder, a tube holder, means arranged to 15 enter the interior of a tube in the holder to support and guide the tube, and mechanism for actuating said last-named means to insert the tube held in the tube holder into a heel in the heel holder.

20 3. In a machine for driving tubes into heels, a heel holder and gage, a rod-like member arranged to enter the interior of a tube and to support an inside wall thereof, a tube indenting tool, and a tube driver arranged to carry a tube 25 past the indenting tool and into a heel in the heel holder.

4. In a machine for driving tubes into heels, heel holding means, tube holding means, means arranged to enter the interior of a tube and to 30 support an inside wall thereof, a tube indenting means and a tube driving means arranged to operate in timed relation, and to indent a tube while it is under the control of the driving means.

5. In a machine for driving tubes into heels, 35 a raceway, a transferring member for receiving tubes from the raceway and placing them in driving position, heel holding means, a driver arranged to drive a tube from driving position in the transferring means into a heel in the heel holding means, and a retaining member for preventing accidental movement of a tube from the 40 transferring member when in driving position.

6. In a machine for driving tubes into heels, a raceway, a transferer for receiving tubes from 45 the raceway and placing them in driving position, heel holding means, a driver arranged to drive a tube from driving position in the transferer into a heel in the heel holding means, a tube indenting tool, and mechanism for operating said 50 transferer, driving means and indenting tool automatically in timed relation.

7. In a machine for driving tubes into heels, means for receiving a tube and holding it in driving position, a heel support, a heel positioning means movable to engage the top-lift end of a heel, and a driver arranged to move a tube from driving position into a heel in the positioning means.

8. In a machine for driving tubes into heels, 60 means for receiving a tube and moving it to driving position, a heel positioning means movable to engage the top-lift end of a heel, and a driver arranged to guide and move a tube from driving position into a heel in the positioning means.

9. In a machine for driving tubes into heels, 65 means for receiving a tube and holding it in driving position, a heel support, a heel positioning means movable to engage the top-lift end of a heel, a driver arranged to move a tube from driving position into a heel in the positioning means, and operating mechanism for moving said positioning means and driver automatically in timed relation.

75 10. In a machine for driving tubes into heels,

means for receiving a tube and moving it to driving position, a heel positioning means movable to engage a heel, a driver arranged to carry a tube from driving position in the receiving means into a heel, indenting means arranged to indent the tube, and operating mechanism for moving said receiving means, positioning means, driver and indenting means automatically in timed relation.

11. In a machine for driving tubes into heels, 10 a tube driver having a reduced portion arranged to enter a tube and to support an interior wall of the tube, and a tube indenting tool arranged to indent the tube while its said wall is supported by the reduced portion.

15 12. In a machine for driving tubes into heels, a tube driver having a shoulder and a reduced portion beyond the shoulder arranged to fit the interior of a tube to be driven and to support an inside wall of the tube, said reduced portion 20 having a depression, and an indenting means arranged to press on an outside wall of the tube opposite to said depression, to form an indentation in the said tube wall.

13. In a machine for driving tubes into heels, 25 a tube driver having a shoulder and a reduced portion beyond the shoulder arranged to fit the interior of a tube to be driven and to support an inside wall of the tube, said reduced portion 30 having a depression, an indenting tool arranged to press on an outside wall of the tube opposite said depression, to form an indentation in the said tube wall, and power mechanism for moving said driver and indenting tool automatically in timed relation, to effect said indentation during movement of the driver.

14. In a machine for driving tubes into heels, a heel holding means, a tube driver having a portion adapted to determine the position of the following end of a tube after being driven, an 40 indenting tool arranged to form an indentation in the tube, and an adjusting means whereby the relation of the indentation to the following end of the tube may be determined.

15. In a machine for driving tubes into heels, 45 a heel holding means, a driver having an abutment to contact with the following end of a tube to be driven, an indenting tool arranged to move transversely to the line of action of the driver, and means for relatively timing the movements 50 of the abutment and of the indenting tool to determine the distance of the indentation from the following end of the tube.

16. In a machine for driving tubes into heels, a heel holding means, a driver having a shoulder 55 to contact with the following end of a tube to be driven, an indenting tool arranged to move transversely to the line of action of the driver, and means for relatively timing the movements of the shoulder and of the indenting tool to determine the distance of the indentation from the following end of the tool, the heel holding means being adjustable toward and from the driver to locate the top-lift end of a heel thereon relatively to the driven position of the following 60 end of the tube.

17. In a machine for driving tubes into heels, a tube driver having a shoulder and a reduced portion beyond the shoulder arranged to fit the interior of a tube to be driven and to support 70 an inside wall of the tube, said reduced portion having a depression, and an indenting tool arranged to press on an outside wall of the tube opposite said depression, to form an indentation in the said tube wall, said driver and in- 75

denting tool being movable to effect said indentation in a predeterminedly limited portion of said tube wall.

18. In a machine for driving tubes into heels, 5 a member for receiving a tube and moving it to driving position having an aperture, one wall of said aperture being straight, and the other wall of said aperture being straight through a portion of its length and having a portion extending 10 transversely from the end of said straight portion in a direction away from said first-named straight wall, and having a shoulder arranged to support the end of a received tube while the preceding tube lies against the first-named straight wall.

19. In a machine for driving tubes into heels, an 15 oscillating transfer member for moving tubes from a receiving position to a driving position, said member having a recess having a reduced portion arranged to fit a tube to be driven and having a straight wall extending into the unreduced portion, and forming a wall thereof, another wall of the unreduced portion joining a second wall of the reduced portion and diverging 20 therefrom, said other wall having an abutment arranged to support a tube clear of the position occupied by a preceding tube in the reduced portion.

20. In a machine for driving tubes into heels, 25 a rotating transfer member for receiving tubes and moving them to driving position formed as a cylinder one end of which has a Y-shaped recess, one side of the Y being straight and the angular side of the Y having a shoulder to support 30 a tube against falling into the straight portion of the recess when the transfer member is holding the preceding tube in driving position, and arranged, when the cylinder is rotated to receiving position, to move from engagement with the 35 said first-named tube and to permit it to move into the leg of the Y.

21. In a machine for driving tubes into heels, 40 a raceway, a rotating transfer member having a

Y-shaped recess, one side of the Y being straight, said transfer member being movable between a position in which the straight side of the Y is in line with the raceway and a position in which the diverging branch of the Y is in line with the raceway, the diverging branch having a shoulder arranged to receive and hold a tube out of the straight part of the Y in the second-described position of the transfer member, and to move from engagement with the tube in the first-described position of the transfer member.

22. In a machine for operating upon heels, an 15 abutment arranged to engage the attaching face of a heel, and a holding means comprising a V-shaped member and a second member opposite the open end of the V-shaped member, resilient means forcing said members together, said members being thus resiliently relatively movable from each other under pressure, and having their edges lying toward the heel beveled, and means for 20 moving the said members into contact with the top-lift end of the heel, whereby contact with the said top-lift end will spread the said members, additionally stress the resilient means, and cause the said members to grip the heel.

23. In a machine for operating upon heels, an 25 abutment arranged to engage the attaching face of a heel, and a holding means comprising a plate carrying between it and a heel to be operated on a V-shaped member and a second member opposite the open end of the V-shaped member, resilient means forcing said members together, said members being thus resiliently relatively movable from each other under pressure, and having their edges lying toward the heel bevelled, and means for moving the said members into contact with the top-lift end of the heel, whereby contact with the said top-lift end will spread the said members, additionally stress the 30 resilient means, and cause the said members to grip the heel and permit the heel to be clamped by the plate.

FRANK T. GENTILE.
